(57) CLAIM

The ornamental design for an insulated dog water bowl, as shown and described.

DESCRIPTION

FIG. 1 is a front elevation view of an insulated dog water bowl showing my new design;

FIG. 2 is a rear elevation view of the insulated dog water bowl;

FIG. 3 is a left side elevation view of the insulated dog water bowl;

FIG. 4 is a right side elevation view of the insulated dog water bowl;

FIG. 5 is a top plan view of the insulated dog water bowl;

FIG. 6 is a bottom plan view of the insulated dog water bowl;

FIG. 7 is a front perspective view of the insulated dog water bowl; and,

FIG. 8 is a side cross-sectional view of the insulated dog water bowl for illustrating a depth of the insulated dog water bowl. The broken line showing of typography is for illustrative purposes only and is not claimed.
